UNITED STATES PATENT OFFICE.

NILS EMEL NORSTROM, OF CHICAGO, ILLINOIS, ASSIGNOR, BY DIRECT AND MESNE ASSIGNMENTS, TO JOHN ANDERSON, OF SALINA, KANSAS, M. E. RICHARDSON, OF STERLING, KANSAS, AND JOHN H. MARTIN, AND H. KEATING.

TELEPHONE-EXCHANGE.

No. 852,575.

Specification of Letters Patent.

Patented May 7, 1907.

Application filed October 4, 1901. Serial No. 77,527.

To all whom it may concern.

Be it known that I, NILS EMEL NORSTROM, a citizen of the United States of America, and a resident of Chicago, county of Cook, and State of Illinois, have invented certain new and useful Improvements in Telephone-Exchanges, of which the following is a specification.

My invention relates to party line telephone exchanges and has for its object improvements in the devices and methods of operating such exchanges.

In the accompanying drawings Figure 1 is a plan of the switching mechanism used at the local stations; Fig. 2 is a section on line 2—2 of Fig. 1; Fig. 3 is an elevation looking in the direction of the arrow 3 of Fig. 1; Fig. 4 is a section on line 4—4 of Fig. 1; Fig. 4^a is an elevation of the ratchet wheel 20 and its support detached, the frame and the pawl-carrying lever being in section on line 4—4 of Fig. 1. Fig. 5 is a plan of Fig. 4, the upper part being removed; Fig. 6 is a diagram showing a central office at the left hand and a local station at the right hand; and Fig. 7 is a diagram showing two additional local stations, all of which local stations are connected to the central office by the wires 100 and 150.

The switching mechanism is supported in a frame J, which frame is made so that it may be secured to a telephone box directly beneath where the generator is supported. The object of this is simply a convenient means of polarizing the armature A¹ of the magnet-cores A—A¹⁰. This is accomplished by the proximity of the permanent magnets of the generator. The armature A¹ may, however, be a permanent magnet itself, and thus be polarized without being placed adjacent to the generator. Adjacent to the polarized armature A¹ is a bar C which is held against stops C² by the springs C¹. In the armature A¹ are pins C³ which engage slots in the bar C. The arrangement is such that the bar and its connections normally hold the armature in its mid-position but permit it to vibrate in either direction under the influence of electric currents sent through the magnet A—A¹⁰. Secured to the armature A¹ is an arm A⁴ which carries a pawl A² that engages the teeth of a ratchet wheel A³, pivoted on a

post A¹². When a current is sent through the magnet in a direction that will cause the armature A¹ to be attracted to the pole A, the pawl A² will drive the ratchet wheel A³ forward. When a current is sent through the magnet in the opposite direction the armature A¹ will be attracted to the pole A¹⁰, an action that results in moving the pawl A² in an opposite direction. When this occurs, a tail-piece A⁷ on the pawl A² strikes a post A⁸, the effect of which is to release the said pawl from the ratchet wheel. The tail-piece A⁷ also strikes a tail-piece A⁶ on the holding pawl A⁵ and also releases it from the ratchet wheel. This action releases the ratchet wheel, when it is returned to its normal position against stop A¹¹ by means of a spring A¹⁵ around the post A¹². Secured to the ratchet wheel A³, and adjustable by means of the screw A¹³, is a pointer or contact maker P adapted to come into electrical contact with a post 54 when the ratchet wheel is moved from its normal position. The distance the ratchet wheel has to be moved before contact between P and 54 depends upon the adjustment of pointer P. In any series of switches connected together the pointers P are located different distances from the contact posts 54, so that when all of the pointers are moved simultaneously they will come successively in contact with their corresponding contact posts 54.

Adjacent to the parts just described is a second magnet B, on the armature of which is a contact piece 68. On the piece 68 is a pin 680 adapted to come into contact with a contact spring 74 when the armature of magnet B is attracted. Pivoted on the post A⁸ is a hooked lever 69 which projects to a position adjacent to the piece 68. These parts are so related to each other that when the armature of B is attracted the piece 68 is caught and held by the hooked lever 69. In this condition 68, 69 and 74 are in electrical connection with each other. On the lever 69 there is a prong 690, and on the lever A⁴ there is a pin A⁹. These parts are so related to each other that when the magnet A—A¹⁰ is operated so as to cause the release of the pawls A² and A⁵, the pin A⁹ strikes the prong 690 and releases the hooked lever 69 from the piece 68.

At the central office there is a metallic ring E provided with a series of holes E¹ in which may be inserted metallic pins. Pivoted at the center of the ring E is an arm E² provided with a contact spring E³ adapted to come into contact with any pins that may be placed in the holes E¹ when the arm E² is turned on its pivot. A spring (not shown) holds the arm E² normally against a contact spring 43 which it presses away from a contact point 44. The arm E² is connected by a train of gears to a contact disk 51, a part of which disk consists of insulating material. The said train of gears is so arranged that the disk 51 will make one rotation while the arm E² is moving a distance between one hole E¹ and the next adjacent one. By a ratchet wheel and a pawl, or other suitable device, the train of gears is set in motion only when the arm E² is moving toward its normal position. The structure of these devices at the central office not being a part of the present application, there is shown in Fig. 6 only so much as is necessary for a clear understanding of how the electrical connections are made. Located adjacent to the disk 51 is a contact spring 50 which makes an electrical connection with said disk once during each rotation thereof. The springs 50 and E³, and the gearing and disk 51, are so related that the spring contacts a pin in a hole E¹ when the spring 50 is in contact with the insulating part of the disk 51.

Located at a convenient place near the ring E are two switch arms S and S¹ which are connected together by a bar S² so that they will move together. They are, however, insulated from each other. In the paths of the arms S and S¹ are rows of contact points S³ and S⁴. The left hand contact points of each row constitute together a pair of contact points from which run wires 47 and 56 to wires 23 and 34 that connect a pair of plugs F. From other pairs of contact points in the rows S³ and S⁴ other wires run to similar plugs in any desired number. There are also at the central office a series of spring jacks, one of which is represented by the springs 17 and 35. It is from these springs that the party lines 100 and 150 run, and there will be as many of these spring jacks as there are party lines running from the central office. Also at the central office are a drop D, a high resistance clearing-out drop D¹⁰, a condenser W, the ordinary operator's sets, and keys and contacts connected as shown in Fig. 6. At each local station there is an ordinary telephone set connected as shown. In the diagrams only one party line is shown, and the description will be for only one line. Obviously, however, different party lines may be connected together by means of plugs inserted in different spring jacks.

In arranging the stations on a party line,

the switch at station No. 1 will have its contact maker P set so that it will be one step of its ratchet wheel from the contact post 54. At station No. 2 this distance will be two steps; at station No. 3 it will be three steps; and so on.

Assuming that the subscriber at station No. 1 wishes to talk to the subscriber at station No. 3, then the operation would be as follows: The subscriber at station No. 1, either before or after removing his receiver, turns the crank of his generator G, when a current flows as follows:—G—10—11—12—13—A³—14—15—16—150—to central office—17—18—19—D—100 back to 20 of station No. 1—21—G. This operates the drop and notifies the operator that a subscriber on the connected party line is calling. The operator then inserts a plug F in the connected spring jack and moves the key 26, belonging to that plug, to the left. Then with both receivers removed the talking circuit between the central office and station No. 1 is: K at the local—22—12—13—14—15—16—150—17—F¹—23—25—26—27—28—K—29—R—30—31—32—33—34—F²—35—36—100 to 20 of station No. 1—37—H—38—39—R—40—K. The subscriber then tells the operator that station No. 3 is wanted, whereupon she moves the switch arms S and S¹ to the contact points connected with the plug previously inserted in the spring jacks, inserts pins in the first and third holes E¹ of the ring E and moves the arm E² away from its normal position. Upon the return of said arm the disk 51 is rotated. During each rotation there is an electrical connection between 50 and 51, and at each connection a current flows as follows:—X—41—42—43—44—45—46—S—47—23—F¹—17—150 to 16 of each station on the line, 15—A¹⁰—A—48—ground at the several stations to ground at the central office—49—50—51—52—53—X. This operates all of the switches on the party line and moves them forward step by step. When the spring E³ touches a pin in the hole E¹, there is another current as follows:—X—41—42—43—44—45—46—S—47—23—F¹—17—150—to 16 of the station which at the moment has its contact maker P on its contact post 54, 15—14—P—54—55—B—20—100 back to the central—36—35—F²—34—56—S¹—57—E—pin inserted in hole E¹—E³—E²—58—52—53—X. As the pins were inserted in the first and third holes E¹, this action will occur in the first and third stations and in these stations 68 will be connected to 69 and 74. It will be observed that the switching mechanisms of all of the local stations move equal distances, and that the contact maker P does not stop at its contact point 54. This contact point is, therefore, not in the talking circuit but is used as a means of permitting a current to be sent through the magnet B, which magnet com-

plete a talking circuit when operated. As soon as the arm E^2 is again at its normal position the operator presses key 26 to the right and turns the crank of her generator, when a current flows:—G—60—61—62—63—64—34—F ^{2} —35—36—100 to 20 of the first and third stations—37—H—65—66—Q—67—68—69—16—150 back to central—17—F ^{1} —23—25—26—70—71—72—G. This operates the ringing magnet Q of both stations. If the subscribers at the calling station has kept his receiver off of its hook, then the current would go only through the third station. When the called subscriber has removed his receiver the talking circuit is as follows:—K at station No. 1—22—73—74—68—69—16—150 to 16 of station No. 3—69—68—74—73—22—K—40—R—39—38—H—37—20—100—station No. 1—20—37—H—38—39—R—40—K. When through talking the subscriber rings off as follows:—G—10—11—22—73—74—68—69—16—150—17—F ^{1} —23—25—D ^{10} —56—34—F ^{2} —35—36—100—20—21—G. This notifies the operator who presses the release key 83 when a current flows as follows:—x—41—42—80—81—49—ground at central to ground at the local stations—48—A—A ^{10} —15—16—150—17—F ^{1} —23—47—S—46—82—83—53—X. This is a current through the switch magnets in the opposite direction to the operating current and the result of it is to release the ratchet wheels A ^{3} and permit them to return to their normal positions.

All of the operating actions except ringing to call a subscriber are independent of whether the receiver is off or on its hook. The condenser W is bridged between ground and the operating line 150, the result of which is that each time a current is sent from the battery X the condenser is charged. Breaking the circuit discharges the condenser, the effect of which is to prevent armatures from sticking to their magnets.

What I claim is:

1. The combination with a party line, and a series of local telephone stations, of a switching device and a telephone connecting device at each station, means for operating the switching devices so as to complete electrical connections to the connecting devices in succession, and means by which electrical impulses may be sent through any desired number of the connecting devices at the times when connections are completed thereto by the switching devices.
2. The combination with a party line, and a series of local telephone stations, of switching devices at the different local stations and connected to the party line so that impulses sent over said line will cause the operation of said switching devices, a telephone set at each station having a normally closed connection to the party line, but arranged to have such connection broken upon the first

movement of the associated switching mechanism, a telephone connecting device at each local station arranged to re-establish the connection between its associated telephone set and said party line, means by which the operation of said switching mechanisms will make electrical connections to the connecting devices in succession, and means by which selected ones of the connecting devices may be operated when connections are completed thereto by said switching devices.

3. The combination with a party line, and a series of local telephone stations each having a normal telephonic connection with said party line, a telephone connecting device at each station arranged to establish telephonic connection between the station and the party line when the normal connection has been broken, means by which upon sending a series of electrical impulses over said party line, the normal telephonic connection of each station will be broken by the first impulse and succeeding impulses will connect the telephone connecting devices in succession to the party line, and means by which selected ones of the connecting devices may be operated by secondary impulses sent over the party line.

4. The combination with a central office, a party line, and a series of local telephone stations each having a normal telephonic connection with the party line, means controlled from the central office for simultaneously breaking the telephonic connections of all local stations, a connecting magnet at each local station by the single operation of any one of which the station at which it is located will be again placed in telephonic connection with the party line, and automatically operating means controlled from the central office for operating selected ones of the connecting magnets so as to place desired stations in telephonic connection with the party line and with each other.

5. The combination with a central office, a party line, and a series of local stations connected to the party line, of switching mechanism at the local stations adapted to be simultaneously and equally operated by impulses sent from the central office, a contact point in the path of each switching mechanism, said contact points being arranged so that upon simultaneous operation of the switching mechanisms connections will be made to the contact points in succession, a connecting magnet connected to each contact point and arranged upon operation to connect its station telephonically to the party line, and means by which electrical impulses may be sent from the central office through two or more selected ones of the connecting magnets at the times when the switching mechanisms make connections to them.

6. The combination with a central office, a party line, and a series of local stations con-

1. The combination with the party line, of a battery located at the central office, switching mechanisms at the local stations adapted to be operated by electrical impulses sent from the central office, a connecting magnet at each local station, said magnets being arranged so that connections will be completed to them in succession by the movements of the switching mechanisms, and means controlled from the central station by which a branch of the impulse sent through the switching mechanisms may also be sent through two or more selected ones of the connecting magnets at the times when connections are made thereto by the switching mechanisms.

2. The combination with a central office, a party line, and a series of local stations connected to the party line, of simultaneously movable contact devices at the central office, a switching magnet and a connecting magnet at each local station, and means whereby upon a series of contacts being made by said contact making devices, each contact made by one of said contact making devices will operate the switching magnets so as to establish connections in succession to the connecting magnets and each contact made by the other contact making device will operate a selected connecting magnet so as to connect its station telephonically to the party line.

3. The combination with a party line, a series of local stations each of which is normally capable of telephonic connections with the line, and means for sending a series of impulses over the line corresponding in number to the stations thereon, of a switching mechanism at each station operated by the impulses sent over the line, means by which the normal telephonic capabilities of all stations are extinguished by the first movement of the switches thereat, means by which the possibility of restoring the telephonic capability is temporarily provided at the stations one by one in the order of the impulses sent, and automatically operating means by which such possibility is transformed into telephonic capability at selected ones of said stations.

4. The combination with a party line, and a series of local stations, of a switching mechanism at each station arranged to be advanced and released by suitable impulses sent over the line, a magnet at each station for connecting it telephonically to the party line, a catch for holding such connection closed, and means operated by the release of said switching mechanism for releasing said catch.

5. The combination with a selecting magnet and a connecting magnet located at a local station in a party line exchange, of a telephonic connection for its station closed by the operation of the connecting magnet, and means for causing said connection to be

broken by an operation of the selecting magnet.

6. The combination with a selecting magnet and a connecting magnet located at a local station in a telephone exchange, of a telephonic connection for the station closed by the operation of the connecting magnet, a hook for holding said connection in a closed condition, and means for releasing said hook by an operation of the connecting magnet so as to break said connection.

7. The combination with a central office, a party line, and a series of local stations, of a telephone set at each station connected by two branches to the party line, one of which branches may be closed by a subscriber at the station and the other of which is closed only by an operation controlled from the central office, a magnet at each station for closing the second branch and itself located in a normally open branch, means controlled from the central office for simultaneously breaking the first branches of all stations and for temporarily closing the connections to the magnets in succession, and means also controlled from the central office for sending an impulse through selected ones of said magnets so as to cause the closure of the second branches at selected stations.

8. The combination with a central office provided with a battery, a party line, and a series of local telephone stations, each of which is provided with a switching mechanism, of a circuit including the party line, the battery and the switching mechanisms of the different stations, a telephone set at each station provided with two branches to the party line, one of which is normally closed and the other of which is normally open, a connecting magnet at each local station located in a normally open branch from the party line, means by which a series of impulses sent over said circuit from said battery will operate to first break the normally closed branches to the telephone sets and then temporarily close the branches to the magnets in succession, means controlled from the central office for sending impulses from said battery through one or more of the temporarily closed branches, and means by which an impulse so sent through a temporarily connected magnet will serve to close the normally open branch to the telephone set.

9. The combination with a party line, a series of local stations, and a switching mechanism at each station for connecting it telephonically to the line, of a telephone connecting magnet at each station, means for operating said switching mechanisms so as to permit the selective operation of any desired number of the connecting magnets, a telephonic connection for each station closed by the operation of the connecting magnet thereat, a hook associated with each connecting magnet for maintaining said connec-

tion in a closed condition, and means for releasing said hook by the release action of the associated switching mechanism.

15. The combination with a party line, a series of local stations, and a switching mechanism at each station, of a connecting magnet at each station, means for operating said switching mechanisms so as to permit the selective operation of any desired number of the connecting magnets, a telephonic connection for each station closed by the operation of the connecting magnet thereat, means for holding said telephonic connection closed, and means for causing said telephonic connection to be broken by the return of said switching mechanism to its normal position.

16. The combination with conductors leading from a central office to a series of local stations, of a switching mechanism at each local station, a magnet at each station for controlling its switching mechanism, a normal contact normally closed by said switching mechanism, a telephone set for each station normally bridged between said conductors through a circuit including said normal contact, means at the central office for sending impulses through said magnets to cause said switching mechanisms to advance step-by-step to break the electric connections at the normal contacts and thereby to disconnect the telephone sets from circuit with said conductors, a second contact at each station adapted to be closed by the associated switching mechanism after a number of impulses have been sent, said second contacts being arranged so that each requires a different number of impulses to cause its closure, a second magnet at each station connected with the central office by the closure of the associated second contact, means for sending an impulse through a second magnet when its second contact is closed, and devices actuated by said second magnet to again connect its telephone set with said conductors.

17. The combination with a central office, a party line, and a series of local stations, of a switching mechanism at each local station, a normal telephonic connection for each station closed by its switching mechanism when in normal position, a second magnet at each station, means controlled from the central office for advancing the switching mechanisms so as to first break the normal telephonic connections of said stations and subsequently to connect the second magnets in succession to the central office, means for sending an impulse through a second magnet at the time that it is connected to the central office, and devices actuated by said second magnets for re-establishing the telephonic connections of their respective stations.

18. The combination with a party line, a series of switching mechanisms, a battery,

and means for sending impulses from said battery over said line to operate said switching mechanisms, of a condenser bridged between the branches of the circuit for said switching mechanisms and so arranged that the charge it receives when an impulse is sent over the line becomes discharged when the impulse ceases whereby residual magnetism of the magnets for said switching mechanism is neutralized.

19. The combination with the two branches of a circuit, a battery, and means for closing connections between said battery and said branches for the purpose of sending a series of impulses, of an electrically operated switching mechanism and a condenser in separate bridges between said branches.

20. The combination with a battery, an electrically operated switching mechanism, and a circuit by means of which impulses are sent from said battery through said switching mechanism, of a condenser bridged between the branches of said circuit and arranged to discharge through said switching mechanism.

21. A party-line subscriber's station having selecting switching mechanism including a releasing-magnet for restoring the selecting mechanism to its normal condition, and a switching device operated by the releasing magnet for opening the signal-receiving circuit.

22. A party telephone-line extending from a plurality of subscriber's stations to an exchange, each subscriber's station having thereat a signaling-generator, a signal receiver or bell, switching mechanism serving, when unset, to permit of operative association between the signaling-generator and the line and between the telephone and the line, and, when actuated, to dissociate the generator and telephone from the line, additional switching mechanism for establishing operative association between the telephone and the line at a selected station, a detent engaging an actuated portion of the additional switching mechanism to hold the same in the position to which it is set, electromagnetic apparatus governing the aforesaid switching mechanisms and also operating to break the engagement of the detent at a selected station, and apparatus at the exchange for governing the operation of the electromagnetic mechanisms at the different stations.

23. A party telephone-line extending from a plurality of subscribers' stations to an exchange, each subscriber's station having thereat a signaling-generator, a signal receiver or bell, switching mechanism serving, when unset, to permit of operative association between the signaling-generator and the line, and, when actuated, to dissociate the generator from the line, additional switching mechanism for establishing operative association between the telephone and the line at

a selected station, a detent engaging an actuated portion of the additional switching mechanism to hold the same in the position to which it is set, electromagnetic apparatus governing the aforesaid switching mechanisms and also operating to break the engagement of the detent at a selected station, and apparatus at the exchange for governing the operation of the electromagnetic mechanisms at the different stations.

24. A party telephone-line extending from a plurality of subscribers' stations to an exchange, each subscriber's station having thereat a signaling-generator, a signal receiver or bell, switching mechanism serving, when unset, to permit of operative association between the signaling-generator and the line, and when actuated, to dissociate the generator from the line, additional switching mechanism for establishing operative association between the signal-receiver and the line at a selected station, a detent engaging an actuated portion of the additional switching mechanism to hold the same in the position to which it is set, electromagnetic apparatus governing the aforesaid switching mechanisms and also operating to break the engagement of the detent at a selected station, and apparatus at the exchange for governing the operation of the electromagnetic mechanisms at the different stations.

25. A party telephone-line extending from a plurality of subscribers' stations to an exchange, each subscriber's station having thereat a telephone, switching mechanism serving, when unset, to permit of operative association between the telephone and the line, and, when actuated, to dissociate the telephone from the line, additional switching mechanism for establishing operative association between the telephone and the line at a selected station, a detent engaging an actuated portion of the additional switching mechanism to hold the same in the position to which it is set, electromagnetic apparatus governing the aforesaid switching mechanisms and also operating to break the engagement of the detent at a selected station, and apparatus at the exchange for governing the operation of the electromagnetic mechanisms at the different stations.

26. A party telephone-line extending from a plurality of subscribers' stations to an exchange, switching mechanism for establishing operative association between the telephone and the line at a selected station, a detent engaging an actuated portion of said switching mechanism to hold the same in the position to which it is set, electromagnetic apparatus governing the aforesaid switching mechanism and also operating to break the engagement of the detent at a selected station, and apparatus at the exchange for governing the operation of the electromagnetic mechanisms at the different stations.

27. A party telephone-line extending from a plurality of subscribers' stations to an exchange, switching mechanism for establishing operative association between the telephone and the line at a selected station, a detent engaging an actuated portion of said switching mechanism to hold the same in the position to which it is set, electromagnetic apparatus governing the aforesaid switching mechanism and also operating to break the engagement of the detent at a selected station, and apparatus for governing the operation of the electromagnetic mechanisms at the different stations.

28. Substation apparatus for party telephone-lines, including switching mechanism serving to control the association of the telephone with the line, a detent for holding the switching mechanism in the position to which it has been actuated, and electromagnetic mechanism for operating the said switching mechanism, to permit the detent to engage the same, and for breaking the engagement of the detent from connection with the switching mechanism.

29. Substation apparatus for party telephone-lines, including switching mechanism serving to control the association of the telephone with the line, a detent for holding the switching mechanism in the position to which it has been actuated, and electromagnetic mechanism for operating the said switching mechanism, to permit the detent to engage the same, and for breaking the engagement of the detent from connection with the switching mechanism, in combination with switching apparatus at an exchange for effecting the operation of said electromagnetic mechanism.

30. A party telephone-line extending from a plurality of substations to an exchange, signaling-generators at the substations, switching mechanism for establishing operative association between the signaling-generators and the line at the different stations, electromagnetic apparatus governing the aforesaid switching mechanism, and apparatus at the exchange for governing the operation of the electromagnetic mechanisms at the different stations.

31. A telephone-line extending from a substation to an exchange, a signaling-generator at the substation, switching mechanism for establishing operative association between the generator and the line, electromagnetic mechanism governing the operation of the switching mechanism, and apparatus at the exchange for governing the operation of the electromagnetic mechanism.

Signed at Chicago, Ill this 16th day of Sept 1901.
